Primary Examiner — Darlington Ly(74) *Attorney, Agent, or Firm* — Schumaker, Loop & Kendrick, LLP; James D. Miller(57) **CLAIM**

The ornamental design for a pneumatic nailer, as shown and described.

DESCRIPTION

FIG. 1 is a perspective view of a pneumatic nailer, a nail magazine and a nailer base shown in phantom lines; FIG. 2 is a top plan view of the pneumatic nailer; FIG. 3 is a rear elevational view of the pneumatic nailer; FIG. 4 is a right side elevational view of the pneumatic nailer; FIG. 5 is a front elevational view of the pneumatic nailer; and, FIG. 6 is a left side elevational view of the pneumatic nailer. The broken lines in the drawings illustrate portions of the pneumatic nailer that form no part of the claimed design.
